UNITED STATES PATENT OFFICE.

ANDREWS ALLEN, OF GLENCOE, ILLINOIS.

COAL-HANDLING APPARATUS.

Application filed March 3, 1923. Serial No. 622,480.

My invention relates to apparatus for handling coal and other materials and has particular reference to an apparatus for loading hoisting skips at the bottom of a mine shaft, and also the provision of a skip having vertical sides, one side of which is angularly disposed with relation to the other side of the skip whereby the lading is so distributed that the filling of the skip is facilitated and the dumping thereof is made easier than is common in devices of this character.

The primary object of my invention is the provision of coal handling apparatus which is as nearly automatic in its operation as possible and by the operation of which the skips are filled to a predetermined capacity at the bottom of the mine shaft and with the hoisting of the skips the loading chute is automatically closed so the lading is prevented from falling into the mine shaft, and when the skip reaches the bottom of the shaft or in loading position the loading spout is automatically turned into loading position so that the coal has a free passageway down into the chute from the weighing pan into the skip.

Another and further object of my invention is the provision of a skip, one side of which extends upward at an angle of approximately 30° from the vertical, which, with the mounting provided between the bail and skip, and also the making of the sides of the skip of different heights and dumping of the skip towards the lower side, causes an easy dumping of the skip with less rotation about its pivotal support and the discharge of the coal therefrom with a minimum amount of shock and therefore wear and tear upon the hoisting apparatus than what has been possible heretofore.

These and further objects of my invention will be more fully and better understood by reference to the accompanying drawings, in which—

Figure 1 is an elevational view of the lower portion of a mine shaft embodying my improved apparatus, partially in section and partially in elevation;

Figure 2 is a detailed vertical sectional view of the lower portion of the mine shaft showing the loading chute and skip in position to receive a load of material;

Figure 3 is a plan view of the lower portion of a mine shaft showing one loading chute in operative position and the other loading chute in closed position.

Figure 4 is a detail view of the latch member serving to hold the skip in position;

Figure 5 is a side elevational view of the segmental operating pulley operating the loading spout and closure therefor;

Figure 6 is a front elevational view of the device shown in Figure 5; and

Figure 7 is a detail sectional view showing the guide roller and shaft upon which the said roller is mounted and which is attached to each of the skips.

Referring now specifically to the drawings, in which like reference characters refer to like parts throughout, a mine compartment 10 is shown having a mine car dumping apparatus 11 positioned therein, the mine car 12 being shown in said dumping apparatus, the dumping apparatus being mounted upon rollers 13 and 14 so that the mine car is overturned and its contents discharged into a weighing pan 15, two of which are provided, although only one is shown in the drawings, which one is suspended from a scale 16, the said weighing pan having a discharge opening 17 at the bottom thereof which is opened and closed by means of a door 18 having a cable 19 secured thereto, the door 18 being controlled by apparatus 20 so that the discharge of the coal from the weighing pan 15 is controlled by the operator. In the lower part of compartment 10 is a frame 21 suitably supported by members 22—22, the frame 21 having a pair of loading chutes 23 and 23^a positioned thereon, the upper ends of which are directly under the discharge chutes 18 from the weighing pans 15 and the lower ends lead downward adjacent the mine shaft 24 and extend into an opening 25 in the side of the mine shaft 24 and which connects the shaft 24 with the chamber 10. The mine shaft 24 is divided into a plurality of parallel extending passages 26 and 27, each of said passages having vertical guides 28 secured to the sides thereof and with which the bail 29 carrying the skip 35 engages as it travels up and down the shafts. The bail 29 is composed of a pair of vertical members 30 and 31 which are connected together at their lower ends by a transversely extending shaft 32 and have suitable connections (not shown) at their upper ends, by means of which the bail 29 is secured to the hoisting cable, and have a plurality of wearing shoes 30^a secured thereto which operate in sliding engagement with the vertical

guides 28.

guides 28—28 at the sides of the shaft, these plates being tapered in longitudinal direction so that the skip is wedged between the vertical bail members 30 and 31 and sidewise movement of the skip is prevented. In the lower portion of the shaft 24 is a floor 33 upon which the lower end of the members 30 and 31, comprising the bail 29, rest when the skip is in position to be filled. A pair of landing shoes 34—34 are secured to the shaft 32, which has mounted thereon the skip 35, one side of which 36 extends upwardly in a vertical direction while the opposite side 37 extends upward and outward at an angle of approximately 30° from the vertical, the skip thus being supported upon the shaft 32 and rotatably mounted upon said shaft for purposes of dumping when the skip is hoisted to the top of the shaft and is lower on the angularly disposed side or dumping side than on the other side. The skip is therefore triangular in shape and is supported at one side of the center of gravity of the load so that when the skip is being dumped there is a shifting of the load in the skip and the discharge of the lading therefrom is facilitated, as the skip is dumped toward its lower angular side and the lading is discharged with less angular motion of the skip than if its dumping-side were straight. By providing a skip having one of its sides angularly disposed such as I have just described and mounting it upon a bail off the center of the lading, the lading when discharged into the skip naturally builds up toward the discharge point of the chute so that the center of gravity of the skip and lading falls to the side of the skip adjacent to the loading chute, or to the right side of the pivot point of the skip (Fig. 2), and prevents any tendency of the skip to dump in the shaft. The relative height of the two sides of the skip is such as to secure the maximum capacity with a skip of triangular shape and predetermined outside dimensions. When force is applied in dumping the skip at the top of the shaft, the center of gravity of the load shifts to the left of the pivot point and the discharge of the lading commences almost immediately and is so rapid and smooth that the shock and breakage common to the dumping of a rectangular skip is entirely eliminated. If the lading will flow on a 45° angle, a skip with a 30° discharge side need be rotated only 105° in order to completely discharge its lading, instead of 135° as required in a rectangular skip. This small angularity of motion has the further advantage of great rapidity and smoothness of discharge, less vertical motion during dumping, which means a lower head frame, and a minimum drop of the lading onto the discharge chute, also a greater load on the bail and cable, which means a better hoisting cycle and evening of power as compared with a rectangular skip.

Pivots mounted upon the shaft 38 is an arcuate shaped door 39 having a discharge spout 40 projecting therefrom and rigidly connected to a pair of segmental pulleys 41 on each side thereof, illustrated in detail in Figures 5 and 6, the said segmental pulleys having a plurality of channels 42 and 43 in the outer face thereof and having a plurality of cables 44 and 45 extending thereover and passing through lugs 46 and 47 thereon by means of eyes 48—48. The cables 44 pass around the members 41 and over pulleys 49 secured to the upper end of the frame 21, which has counterweights 50—50 at the opposite ends thereof movable in guideways 51—51 resting upon the floor of the chamber 10. Extending transversely across the top of the skip 35 is a shaft 52 having guide pulleys 53 and 54 on the outer ends thereof, said shaft being secured to the skip by means of bearing brackets 55—55. Pivotally mounted by means of pins 56—56 upon each side of the shafts 26 and 27 is a pair of sword arms 57 and 58 to which the cables 45 are attached which lead to the segmental pulleys 41 operating the gate 39. The shape of the sword arms 57 is such that when the skip is lowered into the bottom of the shaft the pulleys 53 and 54 engage the said arms 57 at their upper ends (as shown in dotted lines in Figure 1), and as the skip is lowered the arm 57 is pushed backward, turning the segmental gate 39 down into the position shown in Figure 2 and bringing the chute 40 over the upper edge of the skip 35 so that coal or other lading is directed into the skip 35. Guide arms 57a are provided, which are secured to the sides of the mine shaft 27, which support the sword arms at their upper ends and hold them in proper alignment. Upon the skip 35 being filled, the hoisting operation commences and as the car is lifted the counterweights 50—50 turn the segmental pulley 41 in a clockwise direction bringing the gate 39 up over the end of the top chute 23 and closing the end turning its spout 40 in a vertical direction and free of the shaft. The shaft 52 is held in position by means of a lag bolt 58a with the guide pulley 54 having a hub portion on its inner side thereof, with an annular groove 60 therein within one end of a bracket 61, which in turn is held to the skip by means of cap screws 62, so that cotter pins or other means of holding the pulleys 54 and 55 in position is dispensed with.

A pair of locking devices 63 and 64 are provided on each side of the skip (one of such members shown in detail in Figure 4) for the purpose of holding the skip in an upright position with respect to the bail 29. These locking devices consist of a housing 65 on the side of the skip which is secured thereto by means of rivets 66—66 with a latch 67 pivotally mounted on a bracket 68,

the latch having a pin 69 secured thereto around which a coil spring 70 is positioned, which is interposed between the outer wall of the housing 65 and the latch 67, the latch 67 being held in the position shown in Figure 4 in position to engage the bail 30 so as to prevent the skip from turning upon the shaft 32 until after the latch is released. The skip is held rigidly between the upright 10 members of the bail 30 and 31, a wearing plate 72 being secured to each side of the skip and extending across the top thereof, this plate being tapered in end to end relation, as shown in Figure 4, and operating in 15 sliding engagement with wearing plugs 74—74 secured in any suitable manner to the inner faces of the bail uprights 30 and 31, the taper of the plates causing the skip to make a wedge fit between the bail members 20 30 and 31 and holding the skip securely and rigidly in position. The flange 75 on the brackets 55 are provided on each side of the skip to act as a stop and abuts against the upright bail portions 30 and 31 and the 25 wearing plugs 74 secured thereto, so that the skip is locked between the latches 67 and the stops 75 and is also prevented from turning in the bail in a direction opposite to the dumping direction. The latches extend 30 through slots 71 in the sides of the skip and the wearing plates 72 and 73 and engage the wearing plugs 74 when the skip is held in vertical position, so that the skip is held 35 securely in vertical position until the latches are released, usually by a releasing mechanism in the tipple, which consists of a curved angle or track which engages the latches 67 and moves them back against the spring 70 to a point where the beveled end 65^a will 40 slide past wearing strip 75 when the skip is moved forward in process of overturning.

When the skip is lowered after dumping, the beveled end 67^b of the latch 67 slides against the beveled edges of the wearing 45 plugs 74 into proper position where the latch is closed by the spring 70 after the skip has been brought to a vertical position and the latches have been released by the engaging members mounted in the tipple.

The parts hereinabove described are duplicated for the sections of the shaft 27, and it will be understood that a pair of skips may be provided which are secured to each end of a hoisting cable, so that while one is 55 being dumped at the top of the shaft the other is receiving its lading at the bottom of the shaft, one of which is described in detail above, the other skip descending in the passage 27 before the loading chute 23^a, which operates in the same manner and has the same combination of parts as is described herein pertaining to the chute 23, or one skip may be used with a counterweight on the end of the other hoisting 60 cable.

The lading after being dumped from the car 21 into the weighing pan 15 is weighed by the operator and held into position until the skip is at the bottom of the mine shaft, which, as the skip descends, as hereinabove 70 described, opens the discharge chute 23 by turning the gate 39 down into position shown in the drawings (Figures 1 and 2). Thereupon the lading in the scale pan 15 is discharged through the opening 17 by 75 opening the gate 18 and allowing the coal to pass by gravity down through the chute 23 into the skip 35. As soon as this operation is completed, the hoisting of the skip automatically closes the discharge chute 23, so 80 which retains any scattering pieces of coal or other material in the chute 23 until the skip 35 is at the bottom of the shaft ready to receive its lading again, so that the control of this chute is entirely dependent upon 85 the position of the skip and is entirely automatic in its action and its position is such above the skip that the lading is distributed throughout the entire skip.

While I have described more or less precisely the details of construction, I do not wish to be understood as limiting myself thereto, as I contemplate changes in form and the proportion of parts and the substitution of equivalents as circumstances may 90 suggest or render expedient without departing from the spirit or scope of my invention, such as the substitution of a rotary counterweight rigidly connected to the back framework of the gate 39, or the substitution of a strut or cable connection to a lever on the gate 38 as a substitute for the segmental pulley 41.

I claim:

1. Coal handling apparatus comprising in combination a hoisting skip, a bail to which said hoisting skip is pivotally secured, a conveying chute leading to the mine shaft, a pivotally mounted arcuate shaped counterweighted closure member having a discharge 105 spout leading therefrom, a pivotally mounted arm secured to the side of the said mine shaft, means for pivotally mounting said arm in a line parallel with the longitudinal movement of the said hoisting skip the said arm extending substantially in a vertical position, connecting means between the said arm and the said closure member and means upon the said hoisting skip for engagement with the said arm.

2. Coal handling apparatus comprising in combination a hoisting skip, a bail to which said hoisting skip is secured, a conveying chute leading to the mine shaft, a rotatably mounted counterweighted closure member 110 for said chute having a discharge spout at the upper portion thereof, a pivotally mounted arm secured to the side of the mine shaft, the said arm extending in a direction substantially parallel to the direction of the 115

mine shaft, means for mounting said arm on the side of the mine shaft in the path of movement of the said hoisting skip, connections between said arm and said closure member whereby the said closure member is operated, and means upon the said skip for engagement with the said arm.

3. Coal handling apparatus comprising in combination a hoisting skip, a bail to which 10 said hoisting skip is secured, a conveying chute leading to the mine shaft, a rotatably mounted counterweighted closure member for said chute having a discharge spout at the upper portion thereof, a pivotally 15 mounted curved arm, pivotally mounted means on the side of the mine shaft inside of the path of movement of the mine skip, connections between said curved arm and said closure member whereby the said closure member is operated, and means upon the said skip for engagement with the said curved arm.

4. Coal handling apparatus comprising in combination a hoisting skip, a bail to which 25 said hoisting skip is pivotally secured, a conveying chute leading to the mine shaft, a rotatably mounted arcuate shaped closure member for said chute, curved arms mounted upon the side of the mine shaft, a roller carried by said hoisting skip adapted to engage the arms, a segment to which said closure member is secured, connecting means between the said segment and said arm, and a counterweight to operate said closure 30 member in the opposite direction.

5. Coal handling apparatus comprising in combination a hoisting skip, a bail to which 40 said hoisting skip is pivotally secured, a conveying chute leading to the mine shaft, a rotatably mounted arcuate shaped closure member for said chute, curved arms mounted upon the side of the mine shaft, a pair of rollers carried by said hoisting skip adapted to engage the arms, a pair of segments to 45 which said closure member is secured, connecting means between the said segments and

said arms, and a weight adapted to counteract the force exerted by the hoisting skip upon the said curved arms and to return said closure member to closed position.

6. Coal handling apparatus comprising in combination a hoisting skip, a bail to which the said skip is pivotally mounted, stops carried by the said skip on the dumping side thereof, pivotally mounted latch members 55 on the opposite side of said skip adapted to engage said bail, tapered wearing plates on each side of the said skip and cooperating wearing members secured to the said bail whereby the skip is wedged between the upright bail members.

7. Coal handling apparatus comprising in combination a hoisting skip, a bail upon which the said skip is pivotally mounted, transversely extending wearing plates 65 secured to said skip, cooperating wearing plugs secured to the said bail stops on the dumping side of the said skip, latches on the opposite side of said skip adapted to engage the said bail, the said wearing plates and wearing plugs having a wedging effect upon each other when the skip is in upright position.

8. Coal handling apparatus comprising in combination a hoisting skip, a bail to which 75 said hoisting skip is pivotally secured, a conveying chute leading to the mine shaft, a rotatably mounted arcuate shaped closure member for said chute, curved arms mounted upon the side of the mine shaft and having their pivotal point in alignment with the path of movement of the mine skip, rollers carried by said hoisting skip adapted to engage the arms, a crank member carried by 80 said closure member, connecting means between the said crank member and the said arms, and a counterweight adapted to operate said closure member to a closed position.

Signed at Chicago, Illinois, this first day 90 of March, 1923.

ANDREWS ALLEN.
